C. M. DWYER,
VEHICLE WINDOW FRAME,
APPLICATION FILED AUG. 30, 1921.

1,414,399.

Patented May 2, 1922.

Inventor:

Charles M. Dwyer.

R. S. Burns
Attorney

UNITED STATES PATENT OFFICE.

CHARLES M. DWYER, OF LOS ANGELES, CALIFORNIA.

VEHICLE WINDOW FRAME.

1,414,399.

Specification of Letters Patent.

Patented May 2, 1922.

Application filed August 30, 1921. Serial No. 496,842.

To all whom it may concern:

Be it known that I, CHARLES M. DWYER, a citizen of the United States, residing at Los Angeles, in the county of Los Angeles and State of California, have invented new and useful Improvements in a Vehicle Window Frame, of which the following is a specification.

My invention relates to a window frame for the curtains of vehicles, the principal objects of my invention being to generally improve upon and simplify the construction of the existing types of curtain window frame, and to provide a frame of strong and substantial structure that may be easily and cheaply produced and which will be very effective in performing its intended functions.

With the foregoing and other objects in view, my invention consists in certain novel features of construction and arrangement of parts, that will be hereinafter more fully described and claimed, and illustrated in the accompanying drawings, in which:—

Figure 1 is an elevational view of a curtain window frame of my improved construction with parts thereof broken away and in section.

Figure 2 is an enlarged cross sectional perspective view taken approximately on the line 2—2 of Figure 1.

Figure 3 is a cross section of the frame and showing the curtain and glass associated therewith.

Figure 4 is a perspective view of a portion of the frame, the end portions of the frame encircling band and the plate used at the joint between the ends of the band.

Referring by numerals to the accompanying drawings, 10, 10 designate the top and bottom rails of the frame and 11, 11 the end rails; said rails being assembled to form a rectangular frame, the corners of which are preferably rounded.

The rails are preferably formed of wood and formed on the marginal portions of their outer edge are beads or rounded flanges 12.

Formed on the outer portions of the inner edges of the rails of the frame are inwardly projecting flanges such as 13 against which are adapted to engage, the edges of the section of glass 14 that is seated in the frame.

Encircling the frame and positioned in the groove between the beads 12 is a strip or band of metal 15 that is designed to retain

the rails 10 and 11 in assembled relation and to add strength and stability to the frame and the joint between the ends of said metal band is preferably arranged at an intermediate point on one of the rails 10.

Passing through suitably formed apertures in one end of the band are tacks or nails 16 the bodies of which are seated in the rail 10 and said tacks or nails are provided with flat heads 17 that bear against the outer face of the band.

Formed integral with the heads 17 are outwardly projecting shanks 18 that project through apertures 19 in the end portion of the strap that overlies the portion that receives the bodies of the nails or tacks 16, and said shanks 18 also pass through suitably located apertures 20, in the end portions of a plate 21.

This plate 21 overlies the end of the strap having the apertures 19 and it performs the functions of a washer or tie plate when the projecting ends of the shanks are riveted down onto the outer surface of said plate 21 adjacent to the apertures therein.

If desired, plate 21 may also bear the name of the manufacturer or selling agent of the frame.

When the ends of the band 15 are secured to each other and to one of the rails of the frame, a very strong and substantial structure is produced and the frame with a section of glass 14 seated therein may be readily arranged between and secured to the inner edges of the inner and outer walls of a vehicle curtain as illustrated in Figure 3.

Thus it will be seen that I have produced a relatively simple, practical and efficient window frame for vehicle curtains, and the structure of said frame being such that it may be easily and cheaply produced.

While I have shown and described a substantially rectangular frame, it will be understood that my invention contemplates the formation of frames of any desired shape either round, oval or polygonal.

Obviously, minor changes in the size, form and construction of the various parts of my improved window frame may be made and substituted for those herein shown and described without departing from the spirit of the invention claimed.

I claim as my invention:

1. In a vehicle curtain window frame, a series of rails assembled to form a frame, the outer edge of said frame being provided

with a continuous channel, and a metal band seated in said channel and having its ends secured to each other and to one of the rails of the frame.

5. 2. In a vehicle curtain window frame, a series of rails assembled to form a frame, beads formed on the edges of the outer edge of said frame, and a metal band arranged between said beads, the ends of which band are secured to each other and to said frame.

3. In a vehicle curtain window frame, a frame composed of wooden rails, a metal band encircling said frame, the ends of which band overlap each other and fastening devices seated in said frame and passing through the overlapping ends of said band, and the outer ends of said fastening devices being formed into rivets.

4. In a vehicle curtain window frame, a frame composed of wooden rails, a metal band encircling said frame, the ends of which band overlap each other, a plate overlying the overlapping ends of said band and fastening devices passing through said plate, the overlapping ends of the band, and 25 seated in said frame.

5. In a vehicle curtain window frame, a series of wooden rails assembled to form a substantially rectangular frame, a metal band encircling said frame, the ends of 30 which band overlap each other and fastening devices passing through said overlapping ends and seated in one of the rails of the frame.

CHARLES M. DWYER.
